UNITED STATES PATENT OFFICE.

ANTONI NIEDZIELA, OF MANCHESTER, NEW HAMPSHIRE.

CURTAIN-FIXTURE.

1,383,142.

Specification of Letters Patent. Patented June 28, 1921.

Application filed August 2, 1919. Serial No. 314,891.

To all whom it may concern:

Be it known that I, ANTONI NIEDZIELA, a citizen of Poland, residing at Manchester, county of Hillsborough, and State of New Hampshire, have invented certain new and useful Improvements in Curtain-Fixtures, of which the following is a specification.

This invention relates to improvements in curtain fixtures and has as its special object the provision of bracket hangers or fixtures capable of being applied to any ordinary type of window, irrespective of their differing widths, the fixtures being tightly clamped in engagement with the window frame or removed therefrom in a convenient and practical manner.

A further object is to provide devices combined with the fixture for supporting shades or draperies so that separate fixtures for the same are not required.

These and other like objects are attained by the novel construction and combination of parts hereinafter described and shown in the accompanying drawings, forming a material part of this disclosure, and in which—

Figure 1 is a perspective view showing an upper portion of a window frame and indicating the application of the invention, and

Fig. 2 is a fragmentary vertical sectional view taken substantially through the center of the same.

Referring to the drawings in detail, the numeral 10 indicates the side element of a conventional type of window frame with which is connected the mitered upper element 11.

Blanks of sheet metal are cut to form strips 14, bent at right angles forming ends 15, similar bent angles 16 being turned rearwardly from the vertical elements 17 formed integrally with the horizontal strips 14, the bent ends 15 being adapted to be disposed upon opposite sides of the window frame, while the bent elements 16 overlie the frame part 11, resting thereon so as to support a portion of the weight taken by the brackets.

The inwardly extending ends of the horizontal strips 14 are engaged by relatively small rectangular plates 18, secured by rivets or screws 19, which pass through space blocks 20, formed with raised detents 21, engageable with any of the detents or ratchet teeth

22, formed upon the lower side of bars 23, suited to be received in the space between the plates 18, and strips 14.

These bars have screw-threaded stems 24, respectively right and left, and engageable in a turn-buckle 25, by which the bars 23 may be forcibly drawn toward each other, and it will be apparent that if the detents 22 are engaged with the projections 21 that the bracket elements heretofore described are drawn tightly against the outer side of the window frame.

Formed integrally with the vertical strips 17 are forwardly extending arms 26, having spurred points 27, adapted to enter any of a plurality of spaced openings 28, in the drapery pole 29, by which it is supported and held in longitudinal adjustment, the pole being furnished with ornamental balls 30 at its end, and adapted to carry draperies of the usual kind, as indicated by the broken line 31.

A shade roller 32 of the usual type is provided with extending pintles 33, the same entering suitable openings formed in the angular elements 34 of brackets, the feet 35 of which are slotted and held by screws 36 to the vertical elements 17, thereby providing an additional source of adjustment taking care of relatively long or short shade rollers, while obviously the fixtures may be secured on any window commensurate with the spacing of the teeth formed on the bars 33 and the threaded stems engaged therewith.

From the foregoing it will be apparent that the fixtures may be clamped firmly upon the window frame by rotating the turn-buckle 25 or released therefrom by rotating it in the opposite direction, freeing the brackets without difficulty from engagement with the window frame.

Having thus described my invention what I claim as new and desire to secure by Letters Patent, is—

In a curtain fixture, the combination with a pair of metallic plates having horizontal and vertical elements, bent projections formed at right angles with the outer ends of said vertical elements and said horizontal elements, of plates spacedly supported at the front of said horizontal elements near the inner ends thereof, detents engaged between said plates and said strips, bars having ratchet teeth engageable upon said de-

tents, stems formed with said bars having respectively right and left hand threads, a turn-buckle engageable with said threaded stems whereby said strips may be drawn toward each other, arms integrally formed with said vertical elements extending outwardly, spurs on said arms adapted to en-

gage with a drapery pole, and a pair of opposed hanger brackets adjustably secured upon said vertical elements adapted to support between them a shade roller. 10

In testimony whereof I have affixed my signature.

ANTONI NIEDZIELA.
